UNITED STATES PATENT OFFICE.

WILLIAM E. PEARSON, OF BOSTON, MASSACHUSETTS.

STEAM-GENERATOR.

SPECIFICATION forming part of Letters Patent No. 712,405, dated October 28, 1902.

Application filed May 6, 1901. Serial No. 59,028. (No model.)

To all whom it may concern:

Be it known that I, WILLIAM E. PEARSON, of Boston, in the county of Suffolk and State of Massachusetts, have invented a new and useful Improvement in Steam-Generators, of which the following, taken in connection with the accompanying drawings, is a specification.

My invention relates to that class of steam-generating boilers in which it is required to produce comparatively large quantities of steam from small boilers and to produce the same quickly. Heretofore boilers of this class have proved unsatisfactory, for the reason that in use the rapid generation of steam was almost sure to interfere with the circulation of the water, and thus prevent the further generation of steam as well as to cause parts of the boilers to become hot and liable to cause trouble and even explode. The object of my invention is to overcome these defects.

My improved boiler is illustrated in the accompanying drawings, in which—

Figure 1 is a front elevation of my boiler, including the feed-water heater. Fig. 2 is a horizontal section taken on line 2 2 of Fig. 1. Fig. 3 is a side elevation of my boiler and feed-water heaters. Fig. 4 is a rear elevation of the same. Fig. 5 is a diagrammatical sketch to illustrate the flow of water in the generator. In this sketch the parts R⁴ R⁵ R⁶ (shown in Fig. 3) are omitted, as they do not affect the principle of action of my apparatus.

The central feature of my generator consists in its having two separated tanks B and B', one above the other. These tanks have no direct interior connection with each other. They are, in fact, two distinct tanks separated from each other by a clear space S. (Shown in Fig. 3.) Water is fed into the lower tank B from the feed-water heaters H H' through the pipes F², F³, F⁴, F⁵, and F⁶. Water is returned to the tank B through the pipe R⁷ R⁹, as will be explained hereinafter.

The two tanks B and B' are indirectly connected interiorly by means of the manifold tube A, the series of pipes P P P P, and the manifold tube A'. The series of pipes P P P P are arranged as coils (see Figs. 1 and 2) and act as conveyers as well as heaters. The heated water from the tank B flows upward through the manifold A and the coils of pipes to the manifold A' and thence to

the upper tank B', from which it passes through the pipes B², B³, and B⁴ to the steam-liberators B⁵ B⁶. The parts of the liberators that are above the water-level (see Fig. 1) act as steam-domes, from which the steam passes through the pipes S' S² to the engine. 55

The inflow of water may be briefly traced as follows: From the feed-pump or reservoir of water under pressure the water passes through the pipe F to the feed-water heaters H H', thence through the pipes F' F² F³ F⁴ F⁵ F⁶ to the lower tank B, thence through the manifold A and the coil series P P P P and manifold A' to the upper tank B', from which it flows through the pipes B² B³ B⁴ into the liberators B⁵ B⁶. As the heated water makes steam its temperature is lowered, and it will have a tendency to pass to the lowest part of the apparatus—that is, return. I will now describe the return part of my apparatus. The water having lost its high temperature by the act of generating steam will have a higher specific gravity and will seek a lower level, displacing the water in the lower parts. This it does by flowing downward through the pipes R, R², R', and R³ to the upper header-tube R⁴, thence through the uprights R⁵ R⁶ to the lower header-tube R⁶, thence through the pipes R⁷, check-valve R⁸, and pipe R⁹ to the lower tank B, thus causing a constant circulation throughout the entire apparatus. 70 75

The apparatus is covered by a metallic casing, which also includes the furnace or heat-generators. In some cases I prefer to have the headers R⁴ R⁶ and the uprights R⁵ R⁶ outside of the metallic casing. 85

I have not shown any means for generating heat, as I do not wish to confine myself to any particular fuel or method of generating heat. This apparatus is especially adapted to heat-generators in which oil is used as a fuel. 90 95

I claim—

1. In a steam-generator; an upper and lower tank, one placed above the other and without direct interior connection; coils of pipes surrounding the said tanks, the lower ends of the said pipes being connected with the lower tank and their upper ends with the upper tank, substantially as and for the purpose set forth. 100

2. In a steam-generator; an upper and lower tank, one placed above the other and without direct interior connection; coils of steam-pipe surrounding the said tanks, the said steam-pipes being connected at their lower ends with the lower tank, and at their upper ends with the upper tank; steam-liberators connected with said tanks; a system of return-pipes, having a check-valve therein, adapted to receive water from the liberators and return it to the lower tank through said check-

valve, substantially as and for the purpose set forth.

In testimony whereof I have signed my name to this specification, in the presence of two subscribing witnesses, on this 9th day of April, A. D. 1901.

WILLIAM E. PEARSON.

Witnesses:
